LAMP

Frederick Schwartz, Brooklyn, N. Y., assignor to
Artistic Lamp Manufacturing Company, Inc.

Application November 30, 1935, Serial No. 52,297

7 Claims. (Cl. 240—81)

My invention relates to improvements in lamps particularly suited to the use of a multi-filament electric bulb and has among its objects to provide for:

5 1—A portable or semi-portable lamp combining a stand and switch chamber for multi-circuit switches.

2—A stand having a socket and switch chamber for multi-circuit switches and multi-circuit 10 socket for a multi-filament electric bulb.

3—A lamp and stand and multi-filament electric bulb and reflector with said bulb at its focal point.

4—A portable indirect or semi-direct lighting 15 reflector and multi-filament electric bulb whereby illumination of various degrees of intensity may be produced with all degrees of illumination at the greatest efficiency due to the relationship of a single bulb having a multi-filament at the focal point or point of greatest reflecting efficiency for the current consumed at each of the various degrees of illumination.

5—A lamp stand, a switch and bulb chamber 20 at the upper end of the stand and a reflector and single multi-filament electric bulb and an indirect or semi-indirect reflector shaped and located in relation to the filaments of the bulb to effect the maximum illumination from each and all filaments singly or combined with respect 25 to the current consumed.

6—A neat portable lamp for indirect lighting 30 having a reflector and single bulb which produces the desired degree of illumination by switching on one or more filaments in the bulb which by reason of the relationship of the bulb to the reflector gives a maximum efficiency for each or all of the filaments combined.

7—A portable lamp combining direct lighting 35 bulbs with a variable indirect bulb to give variable degrees of illumination as desired by the use of multi-circuit switch forming a part of the lamp permitting the use of a standard current single circuit plug.

I accomplish these and other objects by the 40 construction illustrated in the accompanying drawing forming a part hereof in which;

Figure 1 is a partial section and elevation of my lamp.

Figure 2 is a detailed fragmentary view of the 45 multi-filament bulb and socket as well as a diagrammatic view of the circuit and switch.

Figure 3 is a section of the switch at 3 Figure 4.

Figure 4 is a section of the switch at 4 Figure 5.

Figures 5, 6, 7, and 8 are diagrammatic views showing the various positions of the switch.

Similar reference characters refer to similar parts of my device throughout the several views of the drawing and in the following specifications all of which define the parts as succinctly set forth in the appended claims which cover my invention and for which these Letters Patent have been granted.

My lamp preferably comprises a base (1) into 10 which the electric cord (2) and ordinary plug (3) supply the current from a wall or other house supply socket in the usual manner and which need not be further described as the source of household electric current and its connections to lamps and other electric fixtures have become so common practice that few are unfamiliar with the common use of electric current. The ordinary electric cord or flexible pair of wires after entering the base (1) passes up 15 through the hollow vertical standard (4) to the switch chamber (5) for the direct lighting bulbs (6). The wiring and switch (7) is so arranged that one or more of said bulbs (6) may be lighted from said switch which in its operation 20 is similar to the switch (8) preferably located above the switch (7) and also partially concealed in the switch chamber (5).

The switch (8) is so located, constructed and wired to the socket (9) that one of the wires of 25 the cord (2) may be disconnected thus shutting off the light from the bulb (10) and the circuit from both filaments (A) and (B) as may be seen by referring to Figure 5 of the drawing in which the wire (X) from the plug (3), which is shown 30 to the positive side of the circuit is connected to the spring brush (11).

The switches (7) and (8) are here shown as having four positions of operation, each position shown in one of the Figures 5, 6, 7, and 8. 35

While I have shown a particular type of switch suitable to four operating positions it may be desirable to use a switch suitable for more circuits and therefore more positions of operation than herein illustrated and described. 40

So that the function of my multi-circuit switch may be followed a description of its construction in its simplified form follows: particular reference being made to Figures 3 to 8 inclusive as well as the parts of the 45 switches which may be seen in Figures 1 and 2.

The body of insulating material (12) journals one end of the spindle (13) the other end of which is held concentric to the threaded shank (14) and metal housing (15). Journalized 50

in said threaded shank (14) is the stem (16) which holds the other end of said spindle and one end of the torsion spring (17) coiled around said spindle and having its other end secured to the revolving serrated member (18). The contacts or commutator (19) as may be seen is so secured to said member (18) that there are one less contacts than serrations. Thus where this serration is exposed the insulated surface of the member (18) contacts the brush (11) as shown in Figure 5 of the drawing and no circuit is completed. At this position all filaments of the bulb (10) are not heated and light is off.

By referring to Figure 6 of the drawing it will be seen that a 90° movement of the member (18) and contacts (19) has been made and that the brush (11) connects the commutator (19) which in turn connects the brush (11) and its wire (X) to the brush (20) and its connecting wire (A) and filament (A'). A further 90° turn of the stem (16) and consequent movement of the commutator (19) as may be seen in Figure 7 connects the brush (11) and source of supply wire (X) to the spring brush (21) and the wire (B) and filament (B') which may be of greater illuminating capacity than the filament (A'). By a third 90° movement of the parts the commutator (19) as may be seen in Figure 8 the brush (11) and (X) source of current is connected to both (A) and (B) wires and both filaments.

A' and B' combining the power of illumination of the smaller and larger filaments to give a third degree of illumination and as above stated the number of circuits, filaments and operating positions may be modified to give any number of variations of intensity of light or illumination as desired by modifying the switch and its contacts and movements.

The connections from the switch brushes (20) and (21) and wires A and B may be further followed through their connections to the socket (22) and base (23) of the bulb (10) by referring to Figure 2 of the drawing. The wire A, it will be seen, connects to a yielding ring contact (24) in the socket while the wire B connects to the center contact (25). The parts (24) and (25) have a counterpart (24') and (25') in the base of the bulb thus connecting the filaments (A') and (B') to the wires (A) and (B). The opposite or negative wire (C) connects to the metal internal thread (26) of the socket (22) which contacts the external metal threads (27) of the base (23) of the bulb (10).

Above the switch chamber (5) and preferably connected to it I have provided the socket housing or chamber (28) for the socket (22) and secured to the open upper end of the socket chamber I have provided the reflector (29) which is so shaped and positioned in relation to the illuminated portion of the filaments (A') and (B') that the rays of light therefrom are reflected and projected from the point of illumination of the bulb (10) to the desired coverage of the ceiling of the room thereby at all degrees of illumination the maximum intensity of reflection is produced as may be seen by referring to Figure 1 of the drawing which shows some of the rays of light and their relative angles of projection by the light broken lines.

Secured to the upper edge of the reflector (29) I have provided a framework (30) for supporting the shade (31) and below the reflector (29) and secured to the switch chamber (5) the bulbs (6) for direct lighting are arranged within said

shade and by the use of the switch (7) one or more or all of the bulbs (6) may be turned on as desired.

As these are preferably single filament bulbs and as the circuit for the multi-filament bulb (10) has been described in detail it is for the purpose of brevity that a description of the circuits to each of the lamps or bulbs (6) is here omitted as these bulbs may be connected to their switch (7) in the same manner as the filaments (A') and (B') of the multi-filament bulb (10) are connected to the similar switch (8). Two of three lamps for instance may be connected to a single circuit as described above for the larger filament (B).

The reflector (29) may also be of translucent material permitting partial lighting below from the bulb (10).

I am aware that parabolic reflectors have been used to direct the rays of light from bulbs and arcs to concentrate these rays in beams to obtain the maximum of illumination over a restricted field. It is by the use of a modification of such a reflector for my indirect lighting lamp that I use a new concentration of rays from a lamp having several circuits brought to and centered at a point within the bulb by using filaments of different current consumption which may be lighted one after the other and then collectively to give a light of varying degrees of illumination by the operation of a multi-circuit switch within the lamp thus making it possible to attach the lamp with the ordinary house current and a single circuit cord and plug. By the use of a single bulb positioned at a fixed point within a reflector for indirect lighting that for a given current consumption the light from the smallest filament or the combination of filaments in my multi-filament bulb is projected at the maximum for the current consumed.

It will be seen that no resistance or rheostat is used to vary the illumination from my bulb and that as all light is reflected at a fixed point in relation to my reflector the maximum light is projected as desired to the ceiling and no current is wasted when less light is desired.

By the arrangement of the multi-circuit switch in the lamp, the complication of wires and circuits is confined to the switch chamber of the lamp which has proved an important and valuable advantage as my lamp with its unusual and desirable variations of illumination is plugged into any ordinary wall or fixture outlet.

While I have described and also illustrated one of the several forms and styles of my lamp as now manufactured, I do not wish to be limited to the details as defined in the specifications and drawing but wish to depart therefrom within the scope of the appended claims which succinctly set forth my invention.

I claim:

1. In a portable lamp, having a switch and socket for a multi-filament bulb and a single circuit plug-in cord or source of electric current to said switch, said switch being constructed and arranged to complete the single circuit to each of the filaments of said multi-filament bulb or to all of said filaments.

2. In a portable lamp, having a switch and socket for a multi-filament bulb and a single circuit plug-in cord or source of electric current to said switch, said switch being constructed and arranged to complete the single circuit to each of the filaments of said multi-filament bulb or to all of said filaments, and a reflector having 7

a surface and positioned in relation to the filaments of said bulb to reflect light rays upwardly from one or more of its filaments.

3. A portable lamp comprising a base, a combined multi-circuit switch and socket and a multi-filament bulb secured in said socket, said portable lamp having a single circuit plug and a single circuit electric cord to said switch and means for operating said switch to connect each or all of the filaments in said multi-filament bulb whereby various degrees of illumination may be produced by the operation of said multi-circuit switch.

4. In a portable lamp for indirect lighting wherein the bulb of the lamp is supported by a stand, a two-wire circuit extending through the stand to a switch and socket chamber, a socket for a multi-filament bulb in said chamber, a multi-filament bulb mounted in said socket and a switch in said chamber constructed and arranged to complete the circuit to each of the filaments of said multi-filament bulb or to all of said filaments.

5. A portable lamp comprising a base, a standard, a pair of wires extending from the base upwardly through the standard, a chamber mounted on the top of the standard, three tubular lamp supporting arms branching outwardly from the chamber, a switch in said chamber, wires extending from the switch through the arms to lamps mounted thereon, a second chamber mounted above the first chamber, a lamp socket and a switch in the second chamber, a lamp bulb having two filaments of different wattage in said socket, the last named switch adapted to energize either or both of said filaments, an upwardly directed reflector

surrounding said lamp bulb and a shade mounted above said reflector and extending downwardly around said outer lamps.

6. A portable lamp comprising a supporting base, a hollow standard, a switch and socket chamber mounted on the top of said standard, a multiple switch in the lower part of the chamber, an operator for the switch extending outwardly through an opening in the chamber, a socket for a multiple filament lamp bulb in the upper part of the chamber, a multi-filament lamp bulb mounted and extending upwardly from the socket, said switch being adapted to close a circuit to each filament of the lamp separately or to all filaments in parallel, wires for a single electric circuit extending from the switch downwardly through the standard and connections from the switch to the socket to provide single circuits for each filament and parallel circuits for all filaments.

7. A portable lamp having a hollow standard, a switch chamber mounted on the standard, three incandescent lamp supporting arms extending outwardly from said switch chamber, a switch in said chamber, single circuit wires extending upwardly through the standard and through the switch chamber, a second chamber above said switch chamber, a second switch in said second chamber, a multi-filament lamp socket in said second chamber above the switch and having the socket opening extending upwardly, the second switch being adapted to operate independently of the first switch to connect each of the multiple filaments separately or all at once in parallel.

FREDERICK SCHWARTZ.
